N. Y.

Application July 14, 1936, Serial No. 90,473

1 Claim. (Cl. 155—117)

This invention relates to chairs and has for its object to provide a reclining type chair which is self-adjusting in response to the movement of the occupant. Another object is to provide a device of this sort which has the seat portion pivotally connected to the tilted back so that the seat may be moved forwardly and rearwardly as the inclination of the back is adjusted. A further object is to provide a simple and inexpensive device of this sort which may be easily adjusted with little friction. Yet another object is to provide a pivotal connection between the seat and back which may be loosened or tightened by the occupant while sitting in the chair.

15 Referring to the drawings:

Fig. 1 is a side elevation of a chair embodying this invention.

Fig. 2 is a section on the line 2—2 of Fig. 3.

Fig. 3 is a top plan view of the chair of Fig. 1.

20 Fig. 4 is a detail of the antifriction support and guide, and end portion of the seat.

Fig. 5 is a front view partly in section of the pivotal connection between the seat and back.

Fig. 6 is a right side view of the device of 25 Fig. 5.

In Fig. 1, the chair comprises a back portion 10, having slats 11, or other customary construction, which is pivotally supported at 12 at the rear of the arms 17. A seat 13 is pivotally connected at 14, to the lower end portion of the back below its support 12. The front legs 15 and the rear legs 18, may be of the general shape indicated. For supporting the arms 17 and back, braces or props 16 are provided. Suitable transverse braces 19 and 20 reinforce the under-frame. A metal brace shown by dotted lines in Fig. 1 connects the brace 16, rear legs 18, and the support or pivot 12. A leg and foot rest 21 is pivotally connected at 22 to the front portion of the seat, and is provided with a supporting member 23, which is adapted to rock about its lower end, as the seat 13 is moved forward and backward with changes in the inclination of the back.

40 A metal strip 24 is secured to the front portion of the seat as shown in Figs. 2 to 4, inclusive. A cross or transverse brace 25 between the upper forward ends of the rear legs 18 supports an element having an arcuate anti-friction surface 26. This member having such arcuate surface 26, is screwed or otherwise secured to this cross brace as indicated, though, if desired, it may be made integral with the upstanding guide 28 which is secured by screws entering the holes 30 and passing into the cross brace 25. Instead 45 of the anti-friction surface illustrated, a roller

bearing may be used. The strip 24 is secured to the forward portion of the seat by the upstanding post 27 through which a screw is passed transversely of the seat, and also by a screw passing through the hole 28 into the forward portion 5 of the seat. As shown in Figs. 2 to 4, inclusive, the metal strip 24 takes up the wear of sliding movement of the seat and the guides 29 prevent any lateral shifting of the seat, especially in the forward portion. The guides 29 not only engage 10 the sides of the metal strips 24, but also have overhanging portions 29a which prevent the seat being raised away from the cross base 25.

The pivotal connection between the lower end 15 of the back and rear of the seat includes on each side a fitting 31 extending along a portion of the back and also under the ends of the back at 32. Through this metal fitting which is secured to the back by screws as indicated, is a recess for reception of the pivot pin 14, which, in this case, 20 includes a flat headed bolt 33 which passes through the upstanding projection of member 34, which is secured to the seat. A nut 35 is threaded on the end of the bolt opposite its head, so that on tightening the screw 14, the fitting 25 31 is clamped tightly between the seat supporting member 34 and the nut 35. A projection or wing portion 36 on the nut constitutes a finger piece by means of which the nut may be tightened or loosened to control the ease of adjustment 30 between the back and seat. The movement of the finger piece 36 to the left in Fig. 6 effects a tightening or clamping of this pivotal connection so that the back and seat may be maintained in whatever adjusted position is desired. 35 A washer 37 is placed between the fitting 31 and the supporting member 34 for the seat. It will be understood the clamping mechanism illustrated in Figs. 5 and 6 may, if desired, be used on both pivotal connections, between the back and seat, although in the embodiment illustrated, this connection is located 40 only on one side, as shown in Fig. 3.

In operation, the occupant may sit in the chair 45 in any position of its adjustment, and after being seated, control the inclination of the back to whatever position is desired. By moving the finger piece 36 to loosen the nut 35, this pivotal connection between the back and seat may be loosened so that the back and seat may be adjusted to whatever position is desired by merely conforming the body to the desired position. As 50 the back is inclined rearwardly, for example, to the dotted line portion shown in Fig. 1, the seat 13 is moved forwardly. The finger piece 36 is 55

conveniently manipulated by the chair occupant without difficulty. Instead of having the adjustable locking device applied to the pivotal connection 14, it will be understood that it may be located elsewhere, such for example, as at the pivot 12. The advantage, however, of locating this locking device in the pivotal connection 14, resides in the ease with which it may be manipulated by the chair occupant who can conveniently tighten or loosen this device, with one hand, whereas it would be less convenient to control if located elsewhere. If the leg rest 21 is raised in the position illustrated in Fig. 1, it will be understood that this constitutes an extension 10 of the seat and must also be shifted forwardly as the seat moves with the rearward tilting of the back.

From the drawings it may be seen the pivotal centers of the arms, legs and seat are so spaced 20 that the chair may be folded by moving the back toward the seat and collapsing the quadrangle formed by the brace 16, legs 18, upper portion of the front legs 15, and the arms 17.

I claim:

A folding chair comprising connected side frames, each frame including an arm rest, a forwardly inclined front leg pivoted to the front end portion of the arm rest, a rearwardly inclined rear leg pivoted to the front leg intermediate the ends thereof, a rearwardly inclined brace pivoted between the rear ends of the arm rest and rear leg; a back rest pivoted intermediate its ends to the rear end portion of the arm rests, a seat pivoted to the lower end of the back rest, said seat comprising a frame and spaced longitudinal slats therein, means slidably supporting and guiding the front end of the seat comprising a cross bar connecting the upper ends of the rear legs, transverse metal members having convex upper surfaces on the ends of said cross bar, metal plates on the under side of the seat sliding over the metal members, said metal plates extending inwardly beyond the inner edge of the side bars of the seat frame and guide members secured to the cross bar and having vertical hooks extending over the inner edges of said plates. 10 15 20

JOHN H. VAN WYCK.
